HINGED COMPARTMENTED CONTAINER

John Donald Bostrom, Niles, Ill., assignor to Illinois Tool
Works Inc., Chicago, Ill., a corporation of Delaware

Filed Mar. 15, 1965, Ser. No. 84,261

Term of patent 14 years

(Cl. D58—13)

Fig. 1

Fig. 2

Fig. 3

Fig. 4

Fig. 5

Fig. 6

FIG. 1 is a perspective view of a hinged compartmented container showing my new design as it appears in opened position, the upper portion being similarly compartmented;

FIG. 2 is a side elevational view thereof as it appears in closed position;

FIG. 3 is a view of the bottom container half taken along line 3—3 of FIG. 2;

FIG. 4 is a top plan view of the container;

FIG. 5 is an end view of the container as viewed from the left-hand portion in FIG. 2; and

FIG. 6 is an end view of the container as viewed from the right-hand portion in FIG. 2.

I claim:

The ornamental design for a hinged compartmented container, as shown and described.
